UNITED STATES PATENT OFFICE

EDWARD DIEHL, OF NEW YORK, N. Y.

EYE SHIELD

Application filed September 5, 1928, Serial No. 304,063. Renewed September 25, 1931.

This invention relates to an eye shield and one object of the invention is to provide a shield adapted to be attached to the visor of a hat or cap and including a sheet of transparent material which may be disposed in front of the eyes so that when a workman is grinding tools and the like upon an emery wheel there will be no danger of particles thrown off by the emery wheel striking the workman in the eyes and causing him to be blinded or seriously injured. It will be obvious that the shield could also be employed by stone cutters, persons using an acetylene torch or any one performing work liable to result in injury to the eyes.

Another object of the invention is to provide improved means to mount the transparent sheet beneath the visor of a cap and allow the sheet to be moved from an operative position in which it is disposed in front of the eyes to a folded position close against and substantially parallel to the under surface of the visor where it will be out of the way.

Another object of the invention is to firmly connect the protector with the visor of a cap but at the same time allow it to be easily removed and transferred to another cap.

The invention is illustrated in the accompanying drawings, wherein

Figure 1 is a view showing the improved eye shield in use;

Fig. 2 is a view showing the visor of a cap in section and the shield extending downwardly therefrom in an operative position, the shield being shown in front elevation;

Fig. 3 is a vertical sectional view taken through the hat and shield on the line 3—3 of Fig. 2 with the shield in an operative position, and

Fig. 4 is a view similar to Fig. 3 with the shield folded against the under surface of the visor of the cap.

The eye shield constituting the subject-matter of this invention is intended to be used by workmen in order to protect their eyes from injury and is adapted to be suspended beneath the visor 1 of a hat or cap

2 in front of the eyes, as shown in Fig. 1, and from an inspection of this figure it will be obvious that the shield will serve very effectively to protect the eyes either from flying particles or glaring lights. It could also serve to protect the eyes of aviators or other persons who are subjected to strong air blasts.

The transparent sheet 3 which is to be disposed in front of the eyes to protect the same may be formed of celluloid or any other suitable material and may be either clear or suitably colored. This sheet of material preferably tapers downwardly, as shown in Fig. 2, and in the form illustrated is recessed, as shown at 4, so that it will fit about a person's nose, but it will be understood that the recess may be omitted if so desired. The upper end portion of the sheet is formed intermediate its width with a recess 6.

At opposite sides of the recess 6 the sheet is engaged between the jaws 7 of clamps 8 where it is firmly secured by pressing the jaws into gripping engagement with the sheet or in any other desired manner. Each clamp is formed from a strip of sheet metal bent to define a sleeve 9 from which the jaws 7 extend and through the sleeve of the clamps are passed end portions of a crank shaft 10

formed from a strand of strong wire. The crank 11 of this shaft is between the clamps and since the sheet is formed with the recess 6 the shield may be moved from a depending operative position in front of the eyes to a substantially horizontal position beneath the visor of the hat.

In order to mount the shaft for swinging movement beneath the visor from a lower operative position shown in Figs. 1 and 3 to the inoperative position shown in Fig. 4, I employ a bearing bracket consisting of a strip of sheet metal bent intermediate its length to form a bearing sleeve 12 from which extend arms disposed flat against each other and constituting a shank 13. After forming the shank 13 the arms thereof are bent outwardly and then back upon themselves to form abutments 14 to bear against the under surface of the hat visor and the end portions of the strip constitute prongs 15 which are

passed through the visor intermediate the width thereof. After the prongs have been passed through the visor, a protecting plate 16 having a slit formed therein is fitted upon the prongs and the prongs are bent downwardly so that the visor will be tightly clinched between the prongs and the abutments. It will thus be seen that the protector may be easily applied to a cap of a conventional construction and firmly secured thereto but may be easily removed and transferred to the visor of another cap when a cap is no longer serviceable. Therefore, the protector may be sold as an article of manufacture separate from a cap and applied to a cap by the user.

When the protector is in use, the prongs of the bearing bracket are passed through the visor of a cap and after the protecting plate 16 has been set in place the prongs are bent downwardly and clinched to firmly secure the bracket. The shaft 10 is disposed, as shown in Fig. 4, with the arms of its crank 11 extending rearwardly and the transparent sheet projects forwardly close to the under surface of the visor with its free forward edge terminating slightly to the rear of the marginal edge of the visor. When the protector is so disposed, it will be out of the way and since the sleeves 9 have a certain amount of binding engagement about the end portions of the crank shaft the visor will not be liable to drop downwardly. It should further be noted that the recess 4 is disposed at the center of the visor and, therefore, the visor may be grasped in the usual manner in order to remove a cap or set a cap in place upon a person's head without the thumb which is disposed beneath the visor contacting with the transparent sheet and causing it to be soiled.

When the guard is needed in order to protect a person's eyes, the shaft is swung forwardly until the protecting sheet assumes the position indicated by dotted lines in Fig. 3, and the sheet swung downwardly to the position shown in full lines in this figure. The protecting sheet will then be in the position shown in Fig. 1 and serve very effectively to protect the eyes of a person wearing the cap. If it is found that the shield does not fit properly when in the position shown in Fig. 3, the crank shaft may be rotated to raise or lower the shield and if so desired turned to the position shown in Fig. 4 in order to dispose the shield closer to the eyes. Therefore, the shield may be adjusted vertically and also disposed close to or at some distance from a person's eyes.

Having thus described the invention, I claim:

1. An eye shield comprising a transparent sheet, bearings projecting from the rear edge of said sheet in spaced relation to each other, a crank shaft rotatably received in

said bearings with its crank portion between the bearings, and a fastener adapted to be secured to a hat brim and having a bearing rotatably receiving the crank portion of said shaft to mount the shaft for swinging movement beneath the brim. 70

2. An eye shield comprising a transparent sheet, bearings projecting from the rear edge of said sheet in spaced relation to each other, a crank shaft having its end portions rotatably received in said bearings and its crank portion between the bearings, a recess being formed in the sheet between said bearings to receive the crank portion of the shaft during movement of the sheet, and a fastener 75 adapted to be secured to a hat brim and having a bearing rotatably receiving the crank portion of said shaft to mount the shaft for swinging movement beneath a hat brim, the bearing of said fastener being of sufficient 80 length to prevent movement of the crank longitudinally through the same. 85

In testimony whereof I affix my signature.

EDWARD DIEHL. [L. S.]
